ATTYS.

UNITED STATES PATENT OFFICE.

WILLIAM PENN SHEPARD, OF FALL RIVER, MASSACHUSETTS, ASSIGNOR OF THREE-FOURTHS TO MATTHEW C. YARWOOD, PARKER BORDEN, AND ROLAND G. BUFFINGTON, ALL OF SAME PLACE.

HEAT-REGULATOR FOR INCUBATORS.

SPECIFICATION forming part of Letters Patent No. 394,886, dated December 18, 1888.

Application filed February 15, 1888. Serial No. 264,110. (No model.)

To all whom it may concern:

Be it known that I, WILLIAM PENN SHEPARD, of Fall River, in the county of Bristol, State of Massachusetts, have invented a certain new and useful Improvement in Heat-Regulating Devices for Incubators, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved incubator; Fig. 2, a vertical longitudinal section of the same; Fig. 3, a vertical transverse section; Fig. 4, an end elevation looking from the left in Fig. 1, the boilers and lamp-funnel being removed; Fig. 5, a detail perspective of the sleeve-operating mechanism.

Like letters and figures of reference indicate corresponding parts in the different figures of the drawings.

My invention relates more especially to that class of incubators in which hot water is employed to maintain the heat in the hatching-chamber; and it consists in certain novel features, as hereinafter fully set forth and claimed, the object being to produce a simpler and more effective device of this character than is now in ordinary use.

The nature and operation of the improvement will be readily understood by all conversant with such matters from the following explanation.

In the drawings, A represents the body or case of the incubator, which is provided with the usual egg trays or slides, α , in its interior, and a hinged door, B, in its side, said door being locked by a clasp or catch, b' . The egg-trays α are disposed within an interior case or chamber, C, the walls of which form with the walls of the body A the air-space or insulating-chamber ε , usual in incubators of this class. Inclined or converging partitions g extend from the door B to an opening in the case, C, said door being provided with an inwardly-projecting portion, as shown at m , which is so constructed as to tightly fit the space between said partitions.

The top of the inner case, C, consists of a hot-water tank, D, the bottom of which curves upward, as shown at f in Fig. 3, so that the heat from said tank will radiate toward the center of the case C. A vertical pipe, b , enters the tank D; passes upward through the body A, and is closed by a screw-cap, d , said pipe serving as a supply-pipe, through which the tank may be filled with water.

Two flat pipes, h , are disposed longitudinally on the bottom of the case C, and extend into the air-chamber ε at the rear end of said case, as shown at g in Fig. 2, where they are connected with the tank D by a vertical pipe, i , said pipes h forming the induction-pipes of a boiler, II, hereinafter described.

A centrally and horizontally arranged air box or pipe, K, is longitudinally disposed in the case C directly under the tank D.

A conical boiler, II, is disposed outside the case A at the end opposite the pipe i , said boiler being supported in position by a pipe, k , one end of which is connected with the induction-pipes h , and the other entering the bottom of the boiler, said boiler being also supported by a pipe, l , connected with the tank D, and entering the boiler at the top, as best shown in Fig. 2, said pipe l forming the education-pipe of the boiler.

A lamp, P, by which the heat is imparted to the water in the boiler, is disposed on an adjustable bracket, q , on the body A, in such a position that the chimney of the lamp will stand under the center of the boiler. A conical or funnel-shaped jacket, p , is secured on the pipe l , and so arranged that it embraces or surrounds the boiler, leaving an opening, t , between it and said boiler, which forms an annular flue for the heated air, and also from the smoke and products of combustion from the lamp.

A regulating device for regulating the flame of the lamp is secured to the end of the case A adjacent to said boiler. The regulator consists, essentially, of a lever-bar, r , which has its fulcrum on a knife-edge bearing, v , centrally secured to the end of body A, as seen in Fig. 4. To one end of the bar r is secured a cup, w , which is adapted to contain mercury, and to the opposite end is pivoted a down-

wardly-projecting rod, 12. A crank-rod, 13, is journaled at 14 along the lower portion of the end of the body A, its crank being connected with the lower end of the rod 12 and its opposite end provided with a rigid arm, 44, connected with a sleeve, 45, which is fitted to slide on the wick-tube of the lamp P and regulate the flame thereof. A pipe, 15, leads from one end of the air-chamber K into the cup w, as shown in Fig. 4, said pipe being provided with an annular flange or ring, 17, which serves as a stop to prevent the end of the pipe from entering said cup too far—*i. e.*, so as to touch the bottom of said cup—as the pivoted lever r oscillates. A counterbalance-weight, 20, is disposed on the lever r, to cause said cup to resume its normal position after having been depressed, as hereinafter described.

In the use of my improvement the lamp P on the stand p being lighted and adjusted under the boiler H, the water in the boiler will be heated and pass through the eduction-pipe l into the tank D, and thence through the vertical pipe i, induction-pipes h, and pipe k into the boiler to be again reheated. The hot water in the tank D and said pipes furnish heat for the eggs in the trays x, while by means of the concave bottom f of said tank the heat is concentrated on the box K. In case the temperature in the body becomes too great, the hot air in the box K and pipe 15 will be expanded, and the mercury, which normally stands at a level in the cup w upon both the inside and outside of the lower end of the pipe 15, will be forced out of said tube to a slight extent and into the cup w, containing the mercury, as described, thereby causing said cup to descend by the additional weight of the heavy liquid therein and elevate the opposite end of the lever r. As the end of said lever rises, the crank-rod 13 will be turned to force the sleeve on the wick-tube of the lamp P gradually upward over the flame, thus decreasing the supply of heat to the boiler H

until the temperature within the incubator 45 falls sufficiently to reduce the pressure of the hot air within box K and pipe 15, whereby the mercury will be drawn into the lower end of the latter to an extent, thereby lessening the weight of the heavy liquid in the cup w, when 50 said cup will be raised by the counter-balance 20 and the sleeve on the wick-tube lowered, thereby increasing the flame of the lamp. The rising of the cup w by the reduction of weight therein as the mercury is drawn out of 55 it and into tube 15 at various moments will continue until the cup is stopped by the flange 17 on the pipe 15, when the lower end of the tube will be slightly above the bottom of the cup and still open. If the flange 17 were removed, a careless adjustment of the weight 60 20 might bring the bottom of cup w against the end of tube 15 too early, and proper automatic regulation of the heat would be prevented by the stoppage of the flow of mercury into the 65 lower end of the tube.

As I have made the incubator shown and described the subject-matter of another application for Letters Patent filed December 30, 1887, Serial No. 259,365, I do not herein 70 claim the same broadly.

Having thus explained my invention, what I claim is—

In a heat-regulating device for incubators, the pivoted lever r, provided with the mercury-cup w, and counterbalance-weight 20, the journaled crank-rod 13, provided with the arm 44, and the pitman-rod 12, connecting said crank-rod and said lever, in combination with the pipe 15, provided with the flange 17, for controlling the flame of the lamp and regulating the temperature within the body of the incubator, substantially as described.

WILLIAM PENN SHEPARD.
